UNITED STATES PATENT OFFICE.

ROBERT A. MINKS, OF DEWEY, ILLINOIS.

STACK-FORMING APPARATUS.

1,415,891.

Specification of Letters Patent. Patented May 16, 1922.

Application filed October 25, 1920. Serial No. 419,374.

To all whom it may concern:

Be it known that I, ROBERT A. MINKS, a citizen of the United States, residing at Dewey, in the county of Champaign and State of Illinois, have invented certain new and useful Improvements in Stack-Forming Apparatus, of which the following is a specification.

As is well known to those skilled in the art, straw delivered from the pneumatic stacker of a threshing machine is scattered in a broad half circle thereby, and as the stack grows the straw continually slides down from the top, creating a wide base or foundation, which continues to increase as the pile increases. In order to avoid this, it is the usual custom to employ men to stay on the pile and shape it as it grows. This is disagreeable labor, and it is often difficult, if not impossible, to obtain the necessary workmen for the purpose.

Furthermore, it is the custom to allow the stock of the farmer to have access to the straw stack during the winter season. These feed on the same, and often undermine it, so that it frequently topples over upon the animals.

The primary object of the present invention is to provide an apparatus by which a stack can be effectively formed, and will maintain its shape without the necessity of the workmen being on the pile and arranging the straw thereof.

A further object is to so construct this forming apparatus, that part of it will constitute a permanent means for maintaining the stack and will permit access thereto by the stock without endangering the latter as above set forth.

40 In the accompanying drawing:—

Figure 1 is a plan view illustrating the stack-forming apparatus.

Figure 2 is a view in elevation of a portion of the same on an enlarged scale,

45 Figure 3 is a vertical sectional view,

Figure 4 is a detail view illustrating one means that may be employed for mounting the temporary posts,

Figure 5 is a view in elevation of a modified form of construction,

Figure 6 is a sectional view at right angles to Figure 5,

Figure 7 is another embodiment of the invention.

55 In the structure illustrated two rows of posts 8 are employed arranged substantially

on arcs of concentric circles, as shown more particularly in Figure 1. These posts are permanently set in the ground, and the space between them constitutes the semicircular 60 path of delivery from the ordinary wind or pneumatic stacker of a threshing machine. Secured to these posts are sections 9 of woven wire fabric, preferably fencing, the sections being separable and detachable from the 65 posts. These posts and fencing or wall sections constitute the permanent portion of the apparatus.

Temporarily associated with the posts 8 are higher removable posts 10. In the embodiment illustrated in detail in Figure 4, the permanent posts 8 are tubular, and the temporary posts detachably fit in their upper ends. The fabric sections 9 are secured by detachable hook bolts 11. The posts 10 70 have secured to their upper ends suitable pulleys 12. Wall sections 13, preferably of canvas or other heavy cloth, have secured to their upper corners, cables 14 that pass through the pulleys 12, and may have 75 their free ends fastened in any suitable manner. Cords or cables 15, connected to the lower portions of the sections 13, serve as fastening means for the lower ends of said sections. The temporary posts 10 may be 80 braced by any suitable means, as for instance, stay cables 16 fastened to their upper ends. Preferably also end walls 17 are temporarily mounted on the end posts, as shown in 85 Figure 1.

In use the permanent posts 8 are set at the point where the stack is to be formed, and the wire sections 9 fixed in place thereon. The straw from the thresher is delivered into the space between the inner and outer 90 walls. When this space has been filled the fabric wall sections 13 are placed in position, and are elevated as the stack grows. When the stack is complete the temporary posts 10, wall sections 13 and end walls 17, are removed and may be carried with the thresher to the next job, leaving the pile between the fence sections, which will hold it even though it extends a considerable distance 95 thereabove. It will be noted moreover that stock will have access only to the ends of the pile, and thus danger of the masses falling upon them through undermining is obviated. As the pile decreases, the sections 100 105 9 may be successively removed.

The temporary posts may be secured in place in various ways. Thus in Figures 5 110

and 6 the permanent posts 8^a are solid, and have the wire section 9^a stapled thereto, as shown at 11^a. The temporary posts 10^a are secured to the permanent posts 8^a by suitable yokes 12^a. In Figure 7 the permanent post is designated 8^b and the woven wire wall section 9^b. The temporary post is shown at 10^b and in this instance is bolted to the permanent post, as illustrated at 11^b.

10 From the foregoing, it is thought that the construction, operation and many advantages of the herein described invention will be apparent to those skilled in the art, without further description, and it will be understood that various changes in the size, shape, proportion and minor details of construction may be resorted to without departing from the spirit or sacrificing any of the advantages of the invention.

20 Having thus fully described my invention, what I claim as new, and desire to secure by Letters Patent, is:—

1. In stack forming apparatus, rows of fixed posts arranged substantially on arcs of 25 concentric circles, sections of foraminous material detachably mounted on said posts, auxiliary posts adjustably carried by the upper ends of said fixed posts, means for securing together the auxiliary and fixed posts,

30 fabric sections detachably connected at their lower edges to the fixed posts, pulleys on the upper ends of the auxiliary posts, and cables connected to the upper edges of said fabric sections and passing over said pulleys.

35 2. Stack forming apparatus composed of

a permanent portion and a temporary portion; the permanent portion comprising rows of fixed posts, and flexible wall elements detachably connected thereto, and the temporary portion comprising auxiliary 40 posts detachably connected to the fixed posts and adjustable vertically thereon, fabric wall elements forming a continuation of said flexible wall elements and detachably connected at their lower edges to the fixed 45 posts, and means for adjusting vertically the upper edges of said fabric wall elements as desired.

3. Stack forming apparatus composed of a permanent portion and a temporary 50 portion; the permanent portion comprising rows of fixed posts, flexible wall elements detachably carried thereby and means for attaching the flexible wall elements to said posts, the temporary portion comprising 55 auxiliary posts adjustably carried by the fixed posts, means for fastening the auxiliary posts to the fixed posts, separate wall elements forming a continuation of said flexible wall elements, means for attaching their 60 lower edges to the fixed posts, means for vertically adjusting the upper edges of said separate elements, and means for bracing said temporary posts.

In testimony whereof I affix my signature 65 in the presence of two witnesses.

ROBERT A. MINKS.
